UNITED STATES PATENT OFFICE.

EDWARD ORSON BURROWS, OF SOMERVILLE, MASSACHUSETTS, ASSIGNOR
TO THE SMITH & ANTHONY COMPANY, OF BOSTON, MASSACHUSETTS.

HEATING AND VENTILATING APPARATUS.

SPECIFICATION forming part of Letters Patent No. 594,597, dated November 30, 1897.

Application filed January 28, 1897. Serial No. 621,070. (No model.)

To all whom it may concern:

Be it known that I, EDWARD ORSON BURROWS, of Somerville, in the county of Middlesex and State of Massachusetts, have invented 5 certain new and useful Improvements in Heating and Ventilating Apparatus, of which the following is a specification.

This invention relates to apparatus for heating school-rooms and other apartments where 10 heated air is continuously supplied to the apartment or apartments to be heated, a corresponding volume of air being continuously withdrawn from the apartment. In apartments which are not used at night it is desirable, for the sake of economy of heat, to return the air taken from the apartment back 15 to the heater to be reheated and returned to the apartment; but when the apartment is occupied and a constant supply of air is needed 20 it is desirable to expel the air taken from the apartment into the external atmosphere.

My invention has for its object to provide a simple and efficient heating and ventilating apparatus adapted to attain the ends above 25 mentioned; and it consists in the improvements which I will now proceed to describe and claim.

Of the accompanying drawings, forming a part of this specification, Figure 1 represents 30 a perspective view showing portions of two apartments to be heated and ventilated and the application of my improved apparatus or circulating system thereto. Fig. 2 represents a section on line 2 2 of Fig. 1. Fig. 3 represents a section on line 3 3 of Fig. 1. Fig. 4 represents a section on line 4 4 of Fig. 3. Fig. 35 5 represents a side elevation of the construction shown in Fig. 1.

The same letters of reference indicate the 40 same parts in all the figures.

In the drawings, *a* represents a furnace or other heater, and *b* represents a chamber surrounding the same, which chamber receives the air which is heated and communicates, by 45 means of uptake-flues *c c*, with the apartments *d d* to be heated and ventilated. The uptake-flues *c* may be arranged to deliver air at any suitable point or points in the apartment, there being one uptake-flue *c* for each apartment.

e e represent vertical ventilating-flues, which

communicate at their lower ends with a cold-air chamber *f* and at their upper ends with the external atmosphere, there being one of the flues *e* for each apartment *d*. Each ventilating-flue communicates with the corresponding apartment through an opening *g* at or near the floor of the apartment, said opening having a suitable grating or register, as shown in Fig. 1. Pivoted within each ventilating-flue, at a point opposite the opening *g*, is a damper *h*, which is formed to interrupt the continuity of the flue and when in one position to connect the upper portion of the flue with the opening *g*, as shown in full lines 55 in Fig. 2, the lower portion of the flue *e* being thus shut off from the apartment. When the damper is in another position, as indicated by dotted lines in Fig. 2, it connects the opening *g* with the lower portion of the flue *e* and 60 shuts off the upper portion of said flue from communication with the apartment. It will be seen, therefore, that when the damper *h* is in the position shown in full lines it connects the ventilation-opening *g* with the external air through the upper portion of the 65 ventilating-flue, and when in the position shown in dotted lines it connects said opening with the air-chamber *f* through the lower portion of the ventilating-flue. The air-chamber *f* communicates, through passages *i i*, with the hot-air chamber *b*, surrounding the heater, so that air admitted to said chamber passes 70 to the hot-air chamber and is heated and returns to the apartment through the uptake-flues *c c*.

The operation is as follows: When it is desired to both heat and ventilate the apartment *d*, the damper *h* is adjusted as shown in full lines in Fig. 2, so that the vitiated air 75 from the lower portion of the room is drawn upwardly through the ventilating-flue and escapes into the open air, a constant supply of warmed fresh air being introduced into the apartment through the corresponding uptake *c*. When it is desired to simply keep the apartment *d* warm, without particular 80 regard for ventilation, as during the night, the damper *h* is adjusted as shown in dotted lines in Fig. 2 and causes the air withdrawn 85 through the opening *g* to pass downwardly through the opening *g* to pass downwardly into the air-chamber *f*, from whence it enters 90

95 100

the hot-air chamber *b*, to be there heated and returned to the apartment *d* through the uptake *c*. The air-chamber *f* is provided with a suitable fresh-air inlet *l'*, which is closed when the damper *h* is adjusted to permit the return of air from the apartment *d* to the air-chamber *f* and is opened when the damper is adjusted to permit the air from the apartment *d* to escape into the external air.

10 The damper *h* is preferably made of concavo-convex form in cross-section, so that it presents a curved surface to the current of air issuing from the apartment through the opening *g*, and deflects said current either upwardly or downwardly, according to the adjustment of the damper, at an easy curve, reducing friction to the minimum and therefore facilitating the escape of air from the apartment. The damper is preferably mounted upon a spindle *h'*, which is supported in suitable bearings in the walls of the flue *e*, the axis of the spindle being at the center of a chord of the arc, or at a distance from the concave side. Therefore gravity causes the damper to normally assume the position shown by full lines in Fig. 2. For the purpose of adjusting the damper *h* in opposition to its gravity I provide a chain *h²*, which is connected to the upper edge of the damper

20 and extends forward through a suitable guide in the grating covering the opening *g*. A suitable catch may be provided on said grating to hold the chain when the damper is in the dotted-line adjustment shown in Fig. 2,

25 or the friction of the chain in said guide may serve this purpose. When the chain is released, the damper assumes the full-line position shown in Fig. 2 by gravitation.

I claim—

1. A heating and ventilating apparatus or system, comprising an air-heating chamber, an uptake connecting said chamber with an apartment to be heated, a cold-air chamber communicating with the heating-chamber, a ventilating-flue connected at one end with the cold-air chamber and at the other end with the external air, and communicating at an intermediate point with the apartment through a ventilation-opening, and a damper in said flue adjacent to said opening and subdividing the ventilating-flue into two sections and adapted to direct air from the apartment upward through the upper section to the external air, or downward through the lower section to the cold-air chamber.

2. The combination with a ventilating-flue having an opening which connects it with an apartment to be ventilated, of a damper pivoted in the flue at a point opposite the opening and curved in cross-section, the pivot of the damper being at a distance from the center of its concave side, said damper being arranged to gravitate to connect the upper portion of the flue with said opening and provided with means for positively holding it in opposition to its gravity to connect the lower portion of said flue with the opening.

In testimony whereof I have signed my name to this specification, in the presence of two subscribing witnesses, this 25th day of January, A. D. 1896.

EDWARD ORSON BURROWS.
